N. TESTI

TYPOGRAPHICAL MACHINE

Filed Sept. 25, 1926

UNITED STATES PATENT OFFICE.

NICHOLAS TESTI, OF NEW YORK, N. Y., ASSIGNEE TO INTERTYPE CORPORATION, OF BROOKLYN, NEW YORK, A CORPORATION OF NEW YORK.

TYPOGRAPHICAL MACHINE.

Application filed September 25, 1926. Serial No. 137,793.

The present invention relates to improvements in typographical machines, and more especially to those of the linotype class employing a plurality of matrix magazines which are shiftable to bring one or another thereof into operative position to deliver matrices therefrom to the matrix line assembling means as occasion may require, and to receive matrices returned to it by the matrix distributor; and the primary object of the invention is to provide a simplified and improved means for supporting and shifting the magazines which is capable of shifting the various magazines into and out of operative position without limit with respect to the number of magazines used in the machine.

Heretofore screws, cams, levers and gear motions have been used or proposed for shifting the magazines into and out of working relation with the assembling and distributing mechanisms, but in all such devices there was a limit to their range of operation which restricted the use of such devices to a few predetermined number of magazines. The present invention, on the other hand, provides means which is capable of shifting any number of magazines into and out of working position, and it also provides a novel and improved magazine frame which may be readily coordinated to the number of magazines it may be desired to use in each machine, the invention thus effecting economies in the manufacture of the machines and simplifying and facilitating the magazine shifting operations.

To these and other ends the invention consists in certain improvements and combinations and arrangements of parts, all as will be hereinafter more fully described, the features of novelty being pointed out particularly in the claims at the end of the specification.

In the accompanying drawing:

Figure 1 is a side elevation of magazine supporting and shifting means embodying the present invention, the same being shown applied to a typographical machine wherein the magazines are shifted in a horizontal direction, the uppermost magazine in the stack being shown in operative position.

Figure 2 is a view similar to Figure 1, the magazines, however, being rocked into a rearwardly inclined position for the withdrawal of magazines from the rear thereof.

Figure 3 is a front elevation of the magazine shifting mechanism shown in Figures 1 and 2.

Figures 4, 5 and 6 are side views of the top, intermediate and lower units of the magazine frame shown in Figures 1 and 2.

Figure 7 is a side elevation of a modified form of magazine frame.

Figure 8 is a detail view of a gearing which may be applied to the magazine shifting mechanism to facilitate the operation thereof when a large number of magazines is contained in the machine.

Figure 9 is a side elevation of magazine shifting mechanism embodying the present invention showing the same applied to a stack of magazines which is movable vertically.

Figure 10 represents a detail section taken on the line 10—10 of Figure 9 and looking toward the right.

Similar parts are designated by the same reference characters in the several views.

The magazine shifting mechanism and the magazine frames for use therewith are applicable generally to typographical machines of the class adapted to contain a plurality of superposed matrix containing magazines wherein the magazines are shiftable to bring any one of the magazines as desired into operative position to deliver matrices therefrom to the assembling mechanism of the machine which assembles the matrices into lines and to receive the returning matrices from the matrix distributor. An example of matrix supporting and shifting mechanism in which the matrices are movable horizontally to bring one or another of the magazines into operative position is shown and described in U. S. Patent No. 1,156,031, granted to T. S. Homans on October 5, 1915, the present invention, however, being an improvement upon that disclosed in that patent.

The preferred embodiments of the invention are shown in the accompanying drawing and will be hereinafter described in detail, but it is to be understood that the invention is not restricted to the precise construction shown as equivalent constructions are contemplated, and such will be included within the scope of the claims.

In the present instance, 1 designates portions of the stationary main frame of a typographical machine of the well-known lino-

type class, 2 represents a portion of the assembler entrance which directs the matrices delivered from a magazine in operative position to the assembling mechanism which 5 assembles the matrices into lines, 3 represents a portion of the distributor mechanism to which the matrices are returned after a cast has been made from a matrix line, the distributor, as is well understood by those 10 skilled in the art, delivering the matrices to a channel entrance 4 which returns the matrices to their appropriate grooves or channels in the magazine. The channel entrance 4 is shown pivoted at 5 to the frame 15 of the machine so that it may be swung forwardly into the operative position shown in Figure 1, or it may be swung rearwardly into the inoperative position shown in Figure 2, the channel entrance, while in the 20 latter position, clearing the upper ends of the magazines and thus avoiding interference with the shifting of the magazines to bring one or another thereof into operative position or rocking of the magazines into the 25 rearward magazine removing position.

M , M' and M^2 represent the upper, intermediate and lower magazines in a stack comprising three magazines. These magazines are supported in superposed relation by 30 upper, intermediate and lower magazine frame units 6, 7 and 8. These frame units, as shown in Figures 4, 5 and 6, are of similar construction, each unit being adapted to 35 removably receive and position a magazine on its upper side, and the units are formed with feet or pads 6^a, 7^a and 8^a toward their upper and lower ends whereby when these units are assembled to form a composite magazine frame, the feet or pads 6^a of the 40 upper frame unit will rest on the intermediate frame unit 7 and the feet or pads 7^a on the intermediate frame unit 7 will rest on the lower frame unit 8, the frame units being thus properly spaced, and they may be 45 united in any suitable way, as, for example, by drilling and threading these frame units as shown in Figures 4, 5 and 6 and applying screws in the manner the screw 8^d is shown applied in Figure 1. The feet or pads 6^a and 7^a of the upper and intermediate frame 50 units are properly spaced to enable the intermediate and lower magazines to be accommodated in the chambers formed beneath the upper and intermediate frame 55 units.

The magazine frame carrying the matrix magazines is, according to the present invention, shifted bodily to bring any one of the magazines thereon into operative relationship with the matrix assembling and distributing mechanisms of the machine, by a shifting mechanism, the range of operation of which is unlimited as distinguished from shifting devices such as those heretofore proposed in which the range of opera-

tion was limited, and hence, the present invention provides shifting mechanism which is applicable to the shifting of any desired number of magazines.

In Figures 1 to 8, inclusive, the invention is shown applied to magazines which are shiftable in a substantially horizontal direction to bring the different magazines into working position. In this embodiment of the invention, the shifting mechanism 75 comprises a shaft 9 which is rotatable in bearings formed in or attached to the stationary main frame 1, this shaft having double cranks 10 fixed thereon toward its opposite ends and at the opposite sides of the magazine frame, each double crank having inwardly projecting pins 11 and 12 thereon which are located at diametrically opposite sides of the shaft 9 and preferably 80 on equidistant radii. The cranks 10 are fixed to the shaft 9 so that the crank pins 11 and 12 on both cranks lie in the same plane. The forward ends of the magazine frame units 6, 7 and 8 are formed with recesses or seats 6^b, 7^b and 8^b, respectively, 85 the spacing between these recesses or seats, when the magazine frame units are assembled, equalling the diametrical spacing of the crank pins 11 and 12. Consequently, 90 the crank pins 11 and 12 may engage in the recesses or seats of any two adjacent magazine frame units, the crank pins being shown engaged in the recesses of the upper and intermediate frame units in Figure 1. The 95 upper end of the composite magazine frame is preferably supported by a rail 13 on which one or more of a series of pins 6^c, 7^c and 8^c 100 may rest, a pair of these pins projecting laterally from the upper end of each of the magazine frame units. For example, in Figure 1, the pins 6^c and 7^c are resting on the rail 13. It will be understood that one 105 of these rails 13 is provided on the main frame of the machine at each side of the magazine frame so that the magazines may 110 be supported at both sides.

In order to enable the magazine frame and the magazines therein to be rocked or tilted rearwardly from the normal forwardly inclined position shown in Figure 1 to the rearwardly inclined position shown in Figure 2 for the removal or changing of magazines, one of the magazine frame units, the upper unit 6 in the present instance, has pins 6^d projecting laterally from its opposite sides at points about midway of its length, and the main frame is provided at opposite sides of the magazine frame with arms 1^a which are formed with recesses or seats 14 to receive these pins 6^d whereby the magazine frame and the magazines therein may be supported to rock or tilt about the pins 6^d as an axis. To permit such rocking or 120 tilting movement to take place, each of the rails 13 is pivoted to the frame of the ma- 125 130

chine as on a screw 15 so that the opposite end of the rail may swing vertically, and a locking pin 16 is adapted to be inserted through the frame and into the opposite end 5 of the rail 13, so that this pin, when in position, will lock the respective rail 13 in its normally raised position so that it will act as a support for the pins 6^a, 7^a and 8^a. The free end of each rail 13 may be provided 10 with a handle 17 to facilitate its manipulation.

The operation of the magazine supporting and shifting mechanism as above described is briefly as follows: The magazine frame made up by assembling a number of units corresponding with the number of magazines which it is desired to use in the machine and containing the magazines, is placed in the machine so that the pins 6^a 15 enter and rest in the recesses 14 in the main frame, the frame and the magazines being swung into the forwardly and downwardly inclined position so that the recesses or seats 6^b and 7^b are received by the crank pins 11 20 and 12, and the rails 13 are swung upwardly into the position shown in Figure 1 and each of these rails is locked in such position by insertion of its pin 16. As the rails 13 are 25 swung upwardly into their normal operative position, they receive the pins 6^c and 7^c which support the upper end of the magazine frame. With the parts in this position, the upper magazine M is in operative 30 position, its lower end registering with the assembler entrance 2 so that matrices released from this magazine as by operation of the usual keyboard and the matrix releasing escapements, will be delivered to the usual matrix assembling mechanism, while 35 the upper end of this magazine will be registered with the channel entrance 4 which may be swung forwardly into its operative position, as shown in Figure 1, and hence, this magazine will be in position to receive 40 returning matrices from the usual distributing mechanism which delivers the matrices to the channel entrance 4.

If it is desired to bring the intermediate magazine M' into operative position, the cranks 10 are rotated through a half revolution in an anti-clockwise direction, Figure 1, the shaft 9 having, for example, a crank 18 fixed thereon for operating it. This half revolution of the cranks will cause the pins 45 12 to move in semi-circular arcs above and concentric with the shaft 9, the crank pins 11, at the same time, moving through circular arcs below the shaft 9. The crank pins 11 thus move out of the recesses or seats 6^b on the frame unit 6 while the crank pins 12 which engage in the recesses 7^b of the frame unit 7 act to move the lower end of the composite magazine frame and the magazines thereon through an arc which will first 50 lift the escapements on the upper magazine

M above the escapement actuating reeds on the main frame, then carry the escapements of the upper magazine forwardly and will finally lower the escapements on the intermediate magazine into working relation with 55 the escapement actuating reeds as the intermediate magazine M' assumes the position previously occupied by the upper magazine M. The arcuate movement of the lower or forward end of the magazine frame will 60 lift the pins 6^a out of the open topped recesses 14 in the main frame, and during the arcuate shifting movement of the lower forward end of the magazine frame, the upper 65 rear end of said frame is supported by the pin 7^a as the pin 6^a is lifted upwardly out of contact with the top of the rail 13 while the forward lower end of the magazine frame is swinging in its arcuate path. If it is desired to bring the lower magazine M' 70 into operative position, the shaft 9 is given a further half revolution in the same direction as before, the lower forward end of the magazine frame being thus caused to move 75 in an arcuate path which will remove the intermediate magazine M' from operative 80 position and will bring the lower magazine M' into such position. During this operation, the pin 7^a will rise upwardly out of contact with the top of the rail 13 but the upper rear portion of the magazine frame will be supported by the pin 8^a which then rests on the rail 13. It will be understood 85 that at least one of the pins 6^a, 7^a or 8^a always rests on the rail 13 during the shifting of the magazines, and hence, the upper rear ends of the magazines will be properly supported during the shifting operations.

When it is desired to rock the magazine frame into a downwardly and rearwardly inclined position to permit removal or changing of the magazines, the shaft 9 is rotated in a clockwise direction until the pins 6^a have entered the recesses 14 in the main frame. The pins 16 are then removed and the rails 13 are swung downwardly about their pivots 15 into the dotted line position shown in Figure 2. The composite magazine frame and the magazines thereon may then be rocked into the downwardly and rearwardly inclined position shown in Figure 2, the pins 6^a acting as pivotal supports for the magazine frame and the magazines during this operation. When the magazine frame and the magazines thereon are returned to their normal position, as shown in Figure 1, by swinging them about the pins 6^a as pivotal supports, the crank pins 11 and 12 will automatically receive the open seats 6^b and 7^b, respectively, of the frame units 6 and 7, the operative relationship between the magazine frame and the shifting mechanism being thus automatically re-established.

It will be understood that the magazine

frame may embody an unlimited number of frame units to accommodate any desired number of magazines, and that the shifting mechanism described above will serve to 5 shift the composite magazine frame without limit as to the number of frame units composing it. When a relatively large number of frame units and magazines is used, the weight of the composite frame and the magazines may be considerable, and in order to 10 facilitate the shifting operation, a crank 18^a may be employed which is fixed to a pinion 19 on a shaft 20 which may be journaled in the main frame of the machine, 15 the pinion 19 meshing with a relatively larger gear 21 which may be fixed on the shaft 9, the gear reduction thus provided enabling the composite frame and the magazines thereon to be shifted by the application 20 of less force to the crank 18^a.

Figure 7 shows a modification of the frame units which may be assembled to provide the composite magazine frame. These 25 frame units may all be of duplicate or similar construction, each having a recess or seat 22 at its lower forward end and feet or pads 23 to rest on the next lower frame units. The upper side of each frame unit may be provided with lugs 24 having seats 25 therein to receive the feet 23 of the frame unit next above it and the frame units composing the composite magazine frame may be detachably united by pins 26 inserted into openings 27 formed in the lugs 24 30 and registering openings 28 formed in the feet 23. This construction enables the frame units to be quickly and accurately registered one with the other, both laterally and longitudinally, and the use of the pins to 35 unite the frame units enables these units to be readily assembled in making up the composite magazine frame and it also enables the number of units in the magazine frame to be increased or decreased as desired. 40 The double crank shifting mechanism, as shown in Figures 1, 2 and 3, will cooperate with a magazine frame made up of units as just described in the manner already described in connection with Figures 1, 2 45 and 3, variations in the number of units comprising the magazine frame involving no change in the construction or mode of operation of the double crank shifting mechanism. The upper end of each frame 50 unit is provided with a pin 29 at each side to rest on the rail 13 and thus support the upper rear portion of the magazine frame during the magazine shifting operations.

Figure 9 shows the invention applied 55 to a composite magazine frame and magazines wherein the frame and magazines are shiftable vertically to bring one or another of the magazines into operative position. In this instance, the composite magazine 60 frame comprises frame units 30, all of which

may be of duplicate construction, each frame unit supporting a magazine M³. The frame units are guided by rollers 31 thereon toward their upper and lower ends and at opposite sides and which cooperate with 70 guide rails 32 which may be fixed to the main frame of the machine. In such an arrangement, it will be understood that raising or lowering of the composite frame and the magazines thereon will bring one or 75 another of the magazines into operative relation with the assembling and distributing mechanisms on the machine.

The shifting means in this instance comprises a pair of four-armed cranks 33 and 34 mounted in the main frame at each side of the magazine stack, these cranks being located toward the upper and lower ends of the stack, each crank being provided with a set of four crank pins 35 which project 85 inwardly. These crank pins are adapted and arranged to cooperate successively with recesses or seats 36 which are formed in bosses projecting laterally or outwardly from the respective magazine frame units 90 as shown in Fig. 10 during rotation of the cranks, and thus effect raising or lowering of the stack, according to the direction of rotation of the cranks, thus bringing one or another of the magazines into operative 95 position in substantially the same manner as in the horizontally shiftable arrangement shown in Figs. 1, 2 and 3. Obviously, the cranks in this instance also are capable of 100 cooperating with any number of magazine frame units that may comprise the stack, and units may be added or removed, as occasion may require, without necessitating any 105 change or adjustment of the shifting mechanism. The frame units may be removably bolted or otherwise secured together so that they will be lifted or lowered in unison by the cranks.

The cranks are rotated simultaneously to 110 concurrently raise and lower both ends and sides of the stack by operating means which connects the pair of cranks at each side of the stack to each other and to the cranks at the opposite side thereof. Preferably, a 115 worm gearing is employed for this purpose as it is capable of holding or retaining the stack at different elevations and thus preventing descent thereof under its own weight. As shown, an operating shaft 37 is provided, it being journaled in suitable 120 bearings in the stationary main frame and having worms 38 fixed thereon, these worms meshing with worm wheels 39 which are fixed to the shafts 40 for the cranks 33, the 125 shafts 40 being journaled to rotate in suitable bearings in the stationary main frame at opposite sides of the magazine stack. The shaft 37 is provided with a crank 41 or equivalent means for rotating it. The shaft 37 which operates the pair of cranks at one 130

side of the magazine stack is shown connected by bevel gearing 42 and a cross shaft 43 to a crank actuating shaft at the opposite side of the stack similar to the shaft 37, whereby opposite sides of the stack will be raised and lowered in unison.

The operation of the magazine shifting means shown in Fig. 9 is briefly as follows; the desired number of frame units, each carrying a magazine, are placed in superposed relation between the guides, and any desired magazine in the stack is brought into operative relation with the matrix assembling and distributing mechanisms of the machine by rotating the crank 41 in the appropriate direction to raise or lower the stack, as may be required and through a suitable number of revolutions to bring the selected magazine into the operative position. Raising and lowering of the stack are effected by the successive actions of the different crank pins on the respective frame units, both ends and the opposite sides of the stack, in this instance, being uniformly raised and lowered by the cranks.

The crank motions provided by the present invention for shifting the magazines have an unlimited range of operation, as distinguished from screws, cams, levers and gear motions as heretofore used or proposed, and hence this invention enables an unlimited number of magazine units to be contained in the machine, and magazine units may be added or removed without requiring any change of the shifting means. An advantageous feature of the invention is, that the frame unit for each magazine is provided with or carries its own means to cooperate with the shifting cranks by which such magazine is brought into or removed from operative position, the construction being thus simplified and improved, as each unit may receive its shifting motion directly from the respective crank pin. This invention also enables the frame units to be all constructed alike, thereby facilitating and reducing the cost of construction of the machine.

The cranks and their operating means, which constitute the shifting mechanism, are mounted on and are a part of the stationary main frame of the machine, and hence the shifting mechanism is unaffected by the insertion or removal of the magazine frame units, and moreover, no change or alteration of the shifting mechanism is required when the number of magazine units in the machine is increased or reduced, as the shifting mechanism accommodates itself to any number of magazine units and its position on the main frame remains unchanged.

In the construction shown in Figs. 1, 2 and 3, the pins of the cranks move in a circular path while the cranks rotate on a fixed axis on the main frame, and the successive

engagement of these pins with the seats which are spaced in the direction in which the magazine supporting frame shifts, causes the matrix delivery ends of the magazines to move in a series of substantially cycloidal paths which enables the escapements of a magazine which is in operative position to rise and thus clear the escapement actuating reeds on the main frame, then move forwardly or rearwardly to remove this magazine from operative position and bring the selected magazine into such position, and the final portion of the shifting movement serves to lower the escapements of the latter magazine into working relation with the escapement actuating reeds.

I claim as my invention:—

1. In a typographical machine, the combination of a main frame, means for supporting a plurality of matrix magazines whereby the latter may be shifted to bring one or another thereof into operative position, and means for shifting the magazines comprising a crank rotatable about a fixed axis and having a plurality of crank pins operative to successively act on the magazine supporting means to shift the magazines.

2. In a typographical machine, the combination of a main frame, a plurality of matrix magazine units shiftable therein to bring one or another magazine into operative position, and shifting means mounted on the main frame and embodying a rotatable crank having a plurality of crank pins operative to successively engage and shift the magazine units.

3. In a typographical machine, the combination of a main frame, means supporting a plurality of matrix magazines and shiftable relatively to the main frame to bring one or another of the magazines into operative position, and means on the main frame operative to progressively engage the magazine supporting means, and thereby shift the magazines.

4. In a typographical machine, the combination of a main frame, means carrying a plurality of magazines and shiftable relatively to the main frame to bring one or another of the magazines into operative position, and means for shifting the magazine carrying means embodying a crank having a plurality of pins which are operative during rotation of the crank to successively engage the magazine carrying means at intervals spaced in the direction of shift thereof.

5. In a typographical machine, the combination of a main frame, means carrying a plurality of magazines and shiftable relatively to the main frame to bring one or another of the magazines into operative position, said magazine carrying means having seats spaced at intervals in the direction of

shift, and a crank having eccentric pins operative during rotation of the crank, to successively engage the spaced seats on the magazine carrying means.

5 6. In a typographical machine, the combination of a main frame, means carrying a plurality of matrix magazines and shiftable relatively to the main frame to bring one or another magazine into operative position, 10 said magazine carrying means having seats spaced in the direction of shift, and shifting means on the main frame embodying a crank rotatable about a fixed axis and having a plurality of eccentric pins operative, 15 during rotation of the crank, to successively engage and disengage the seats in said magazine carrying means and thereby shift the same.

7. In a typographical machine, the combination of a main frame, means carrying a plurality of matrix magazines and shiftable relatively to the main frame to bring one or another magazine into operative position, and a crank having pins thereon movable in 25 a circular path and operative successively on an end of the magazine carrying means to move the matrix delivery ends of the magazines in a series of substantially cycloidal paths.

23 8. In a typographical machine, the combination of a main frame, magazine carrying means shiftable relatively to the main frame to bring one or another of a plurality of magazines thereon into operative position, 30 said means having a series of engaging portions spaced in the direction of shift, and a crank rotatable about a fixed axis on the main frame and having a plurality of eccentric pins operative in a circular path to successively act on said engaging portions on the magazine carrying means and thereby shift the latter in a series of substantially cycloidal paths.

45 9. In a typographical machine, the combination of a main frame, a magazine frame comprising a plurality of units each adapted to contain a matrix magazine, and a crank rotatable about a fixed axis and having a plurality of eccentric pins which are mov-

able in a circular path and are operative to 50 successively engage the respective units of the magazine frame to shift it.

10. In a typographical machine, the combination of a main frame, a magazine frame comprising a plurality of frame units each 55 adapted to contain a matrix magazine and having a seat therein, and a crank rotatable on a fixed axis on the main frame and having a plurality of eccentric pins movable in a circular path and operative to successively 60 engage the seats in the respective frame sections to shift them.

11. In a typographical machine, the combination of a main frame, a magazine frame adapted to contain a plurality of matrix 65 magazines and shiftable relatively to the main frame to bring one or another of the magazines into operative position, the main frame having seats therein and the magazine frame having projections to rest in said seats 70 and thereby support the magazine frame to rock into magazine removing position, and a crank rotatable about a fixed axis on the main frame and having pins movable in a circular path to successively engage and 75 shift the magazine carrying frame and to engage and disengage the projections on the magazine frame with respect to said seats in the main frame.

12. In a typographical machine, the combination of a main frame, a magazine frame adapted to contain a plurality of matrix magazines and shiftable to bring one or another of the magazines into operative position, means on the main frame for shifting 80 one end of the magazine frame, means on the main frame to intermediately engage and rockably support the magazine frame when the latter is shifted into a predetermined position, and a rail cooperative with the opposite end of the magazine frame to support it during its shifting movements, said rail being movable to permit rocking of the magazine frame when the latter is supported 85 intermediately.

In testimony whereof I have hereunto set my hand.

NICHOLAS TESTI.
